INTERNAL COMBUSTION ENGINE

Daniel F. Hunt, Buffalo, N. Y.

Application May 3, 1933, Serial No. 669,157

10 Claims. (Cl. 123—16)

My invention relates in general to internal combustion engines, and in particular to an internal combustion engine of the rotary type.

One of the principal objects of my invention 5 has been to provide a rotary internal combustion engine of the two-cycle type, in which there shall be a positive suction of the incoming charge and compression thereof by the employment of a number of cylinders and pistons reciprocating 10 in such cylinders.

Another object has been to provide an engine in which the full energy provided by the charge of gas in the expansion chamber shall be utilized.

15 Another object has been to provide efficient means for cooling the engine so as to remove from it the radiating heat caused by the burning of the gases.

Another object has been to provide for proper 20 lubrication of the working parts and a separation and recovery of the lubricant which passes out through the exhaust port.

Moreover, my invention provides convenient 25 and durable means for reciprocating the pistons within the cylinders of the device.

Moreover, it has been an object to provide an engine of two-cycle type in which the burned gases shall be substantially completely scavenged from the expansion chamber and accomplished 30 in a positive manner.

Furthermore, my device is simple in design, of relatively few working parts, and capable of long life.

The above objects and advantages have been 35 accomplished by the device shown in the accompanying drawings, of which:

Fig. 1 is an end sectional elevation, taken on line 1—1 of Fig. 2.

Fig. 2 is an enlarged, transverse, sectional 40 view, taken on line 2—2 of Fig. 1.

Fig. 3 is a fragmentary, transverse, sectional view, taken on line 3—3 of Fig. 1.

Fig. 4 is a reduced, fragmentary, end, sectional elevation, and is taken on line 4—4 of Fig. 2.

45 Fig. 5 is a fragmentary, reduced, front view of my engine.

Fig. 6 is an enlarged, fragmentary, transverse, sectional view of a modified form of construction.

50 Fig. 7 is an enlarged fragmentary, transverse, sectional view, showing one form of ignition means, taken on line 2—2 of Fig. 1.

Fig. 8 is a fragmentary, sectional view of the ignition device and is taken on line 8—8 of

5 My invention comprises a centrally arranged, stationary shaft 10 which supports the parts of the structure. At one end of this shaft I preferably form a disc-like supporting frame 11, which forms a part of the casing of the motor and the support for the stator thereof. This frame is formed with a web 12 and with radiating reinforcing ribs 13. An annular flange 14 is provided on the supporting frame and is joined to the shaft by means of the web and reinforcing ribs. The shaft 10 is preferably provided with a hole 15 extending through its central portion, such hole terminating short of the rear end 16 thereof, whereby a solid wall 17 is provided. The hole 15 terminates at the front 18 end 18 of the shaft.

A rear rotor supporting disc 25 is rotatably mounted near the rear end 16 of the shaft 10 and within the supporting frame 11. A front rotor supporting disc 26 is rotatably carried by the front end 18 of the shaft in interspaced relation with the disc 25 and each of these discs is mounted upon suitable roller bearings 27. The rotor supporting discs 25 and 26 support and rotatably carry the rotor 28 of my device which 25 will be hereinafter described.

A front supporting frame 30 is arranged at the front side of the motor and in interspaced relation with the rear supporting frame 11. This supporting frame is provided with an annular 30 hub 31 within which a roller bearing 32 is mounted. The outer ring 33 of the bearing is carried by the hub 31 and the inner ring 34 of this bearing is carried upon an outwardly extending ring 35 formed at the center of the rotor 35 supporting disc 26. This rotor supporting disc is, therefore, rotatably mounted between the bearing 27 carried by the front end 18 of the shaft 10 and the hub 31 of the supporting frame 30. The supporting frame 30 is provided with a web 36 and with an annular flange 37 around the outside thereof. Radiating, reinforcing ribs 38 are carried by the web and extend from the hub 31 to the annular flange 37. An annular 45 plate 39 secured to the hub 31 serves to close the inner bearing chamber and is provided in its inner periphery with suitable packing means 40 whereby the joint between it and the ring 35 is sealed against leakage of lubricant. The web 36 of the 50 supporting frame 30 is provided with a plurality of openings 45 arranged in its central portion and also with a number of elongated holes 46 near its periphery. Extending inwardly from the disc and preferably just inside the annularly ar- 55

55 Fig. 7.

ranged openings 46 is an annular baffle flange 47, to be hereinafter described.

Carried by the rear supporting frame 11 is a rear stator side plate 50 which is composed of two annular rings 51 and 52. The rings are held in interspaced relation by a number of radially arranged ribs 53 whereby a plurality of air spaces 54 are formed. The ring 52 is secured to the annular flange 14 of the frame by any suitable means, such as the bolts 55. A front stator side plate 56 is located adjacent the front supporting frame 30 and is formed with an annular flange 57 and an annular flange 58. These flanges like those of the rear stator side plate 50 are held in interspaced relation by means of a number of integral, radially arranged ribs 59, whereby a plurality of air spaces 60 are provided. Near the inner periphery of the front stator side plate 56 is formed an annular baffle ring 61 which overlaps the baffle ring 47 of the supporting frame 30 and which is in interspaced relation therewith so that they may have free relative rotation but are sufficiently close so as to baffle the cooling air currents passing through the motor, as hereinafter described.

Mounted between the annular flanges 51 and 58 of the stator side plates 50 and 56 is the stator 65 of my device. This stator is provided with side flanges 66 which engage with the annular flanges of the stator side plates, and between these side flanges and the annular flanges just mentioned, I provide suitable packing 67. This packing is let into suitable recesses so that a portion of the packing is contained in each of the parts. The upper portion of the stator is slightly eccentric with respect to the lower portion thereof and the rotor 28, as shown in Fig. 1, thus forming expansion chambers 68 between the said rotor and inner wall of the stator. Each of such chambers starts at the point where the eccentric portion of the stator joins the concentric portion of the rotor at the ignition side of the stator and extends to the preceding leading bar.

In the inner working face of the stator there is formed a plurality of intake passageways 70. These passageways are preferably two in number and semi-circular in cross-section. They extend from a point where the concentric portion of the cylindrical surface of the stator commences and extend around in the direction of rotation of the rotor a distance sufficient to insure that the engine will get a supply of fuel during its suction stroke, as hereinafter clearly defined. The stator is provided with an intake sleeve 71 having an intake passageway 72 which communicates with the intake passageways 70. The carburetor (not shown) of the device is attached to the flange 73 of the sleeve. Immediately above the formation of the suction passageways 70 and at a point where the eccentric expansion chamber 68 substantially terminates is formed an elongated exhaust port 74. This port which is preferably semi-circular in cross-section extends around the circumference of the stator a sufficient distance so as to insure that all of the exhaust gases will be expelled from the expansion chamber. An exhaust sleeve 75 having an exhaust passageway 76 is carried by the stator and communicates with the exhaust passageway. Carried by a flange 77 formed on the sleeve is an oil separator 78 of any suitable construction but preferably having baffle plates 79, whereby the oil which may be entrained with the exhaust gases will be removed from the gases and allowed to settle in the sump 80 of the sep-

arator. A suitable outlet 81 is formed at the bottom of the separator and the oil may be removed from the sump through this opening and conducted to any desired place, preferably back to the oil reservoir of the device, as hereinafter described. A plurality of annular radiating fins 82 are formed around the outside of the stator for cooling purposes. A sheet metal jacket 83 is arranged about the stator and is in interspaced relation with it and extends from the annular flange 14 of the supporting frame 11 to the annular flange 37 of the supporting frame 30. These annular flanges, as shown in Fig. 1, are slightly larger in diameter than the diameter of the stator side plates 50 and 56, whereby space 15 is provided between the inner surface of the jacket and the outer ends of the spaces 54 and 60 formed in the side plates. A plurality of inwardly extending annular baffle plates 84 are carried by the jacket and are arranged in staggered relation with the annular radiating fins 82, whereby a tortuous passageway is provided between the fins and baffle plates, as hereinafter described.

The rotor 28 which is rigidly secured and carried by the rotor supporting discs 25 and 26 is mounted between and in sliding contact with the inner faces of the annular flanges 51 and 58 of the stator side plates 50 and 56, respectively. The rotor is provided with a peripheral portion 35 and with opposite side wall portions 86. A suitable semi-metallic packing 87 is arranged in an annular groove 88 formed at each side of the rotor. One-half of each of these grooves is preferably formed in each of the walls 86 of the rotor 35 and the other half is formed in the annular flanges 51 and 58 so that the joint between the stator side plates 50 and 56 and the rotor will be sealed against leakage.

The rotor of my device is provided with a number of reciprocating pistons 90 which are radially arranged and mounted for reciprocation within an equal number of cylinder sleeves 91, 92 and 93. The sleeves are slidably mounted within cylinders 94 which form an integral part 45 of the rotor. Each of the sleeves has an outer surface which is concentric with the outer periphery of the rotor and each is provided at its outer end with a flange 95 which extends part way over the cylinder 94, a suitable counterbore 50 being provided for the reception of this portion of the flange, the remaining portion of the flange extending inwardly toward the center of the sleeve where a centrally arranged opening 96 is provided. The inner surface is preferably conically formed, as shown in the drawings, and the head of each piston is also conically shaped so as to fit the surface of the inner portion of the flange. Suitable and well known packing (not shown) may be placed between the sleeve flange 60 95 and the surface of the piston head. A projection 97 is formed on each cylinder which fits into the opening 96 of the sleeve. A cap 98 is fitted over the inner end of each of the sleeves and formed with an opening for the passage of 65 the part 99 of the piston rod 100. The other part 101 of the piston rod is slidably mounted in the bearing 102 of a follower 103. This follower is rotatably mounted upon the shaft 10.

The parts 99 and 101 of the piston rod 100 are 70 preferably tubular and are connected by means of a yoke 104. The yoke carries a laterally arranged roller pin 105 on each end of which is arranged a roller 106. The follower 103 is centrally arranged on the shaft 10 and between this 75

follower and each of the rotor supporting discs 25 and 30 is located a cam disc 107. Each cam disc is rigidly attached or keyed (as shown) to the stationary shaft 10 so that it is non-rotative. 5 The cam discs are each formed in their adjacent faces with a cam groove 108. This groove is so formed that the upper portion or that portion which is opposite the eccentric portion of the stator is concentric with the shaft 10. The portion below this portion is, however, so formed that the groove approaches the center in a radial direction from each end of the concentric portion by means of which either of the pistons as they pass around over the concentric portion of 15 the stator are first drawn into their respective sleeves and then forced outwardly as shown in Fig. 1. The rollers 106 are, of course, disposed in the grooves 108 and serve through the yoke 105 to cause the pistons to travel as just above 20 described.

A leading bar 110 is provided for each piston and is located somewhat in advance of the piston. These leading bars serve to seal the expansion chamber and to receive the pressure of the expanding gases, the resulting force of such pressure being thereby transmitted to the rotor, causing it and all parts carried by it to rotate and transmit its power to the place of use. Such leading bars also serve to seal the expansion chambers until the exhaust port is reached. Each of these bars is preferably semi-circular on its underside and is mounted within a holder 111 having a recess of similar shape. Each of the holders is mounted within a suitable well or recess 112 which is formed as an integral part of the rotor 28. Obviously, the leading bars and holders extend to the opposite sides of the rotor and are in sliding contact with the flanges 51 and 58 of the stator side plates 50 and 56, respectively, as shown in Fig. 3. The outer engaging surface of each leading bar is made to conform to the inner peripheral surface of the stator 65. The leading bars may be held in contact with the inner periphery of the stator by any suitable means, but the centrifugal force created by the rotation of the rotor will ordinarily be sufficient to seal the bar.

In order to facilitate the cooling of the device, the rotor is provided with a central annular wall or septum 115. This septum extends around the interior of the rotor and terminates at the cylinders 94. Formed in the septum at a point near the outer circumference of the rotor is a plurality of elongated recesses 116. The septum is extended inwardly toward the cam discs 107 by means of a number of arcuate flanges 117, each having two laterally extending legs 118 at its inner edge. These legs are arc shaped and extend over and in close proximity to the peripheries of the cam discs and act as deflectors for the air. The cam discs where the eccentric portion of the groove is formed are made circular by outwardly extending webs 119. These webs have flange portions 120 which co-act with the laterally extending ends 118 to deflect the air.

The part 99 of each of the piston rods 100 is connected at its outer end to a tubular piston pin 121 by means of a bearing member 122, to which the outer end of the tubular part 99 of the piston rod is connected.

The front rotor supporting disc 26 is provided with a plurality of openings 123 which are separated by means of arms 124 which are inclined so as to provide vanes or fan blades. These arms 75 are located opposite the openings 45 in the front

supporting frame 30 and as the rotor is revolved they serve to draw air in through the openings 45 and to force it through the openings 123. This air is forced against the front cam disc 107 and is carried outwardly toward the outer periphery 56 of the rotor and between the side wall 86 thereof and the front face of the septum 115. The arcuate flanges 117 with their laterally extending legs 118 serve to prevent the air from passing across to the opposite side of the septum. The air 101 passes to the opposite side of the septum through the elongated openings 116 formed therein and then passes inwardly between the opposite side of the septum and the opposite wall 86 of the rotor toward the shaft 10. Openings 125 are 156 formed in the rear rotor supporting disc 26 near the bearing hub 126 thereof and the air which is forced inwardly is conducted through these openings 125 and outwardly in a radial direction on the outside of the rotor supporting disc 25 201 and between it and the rear supporting frame 11. The rear supporting disc 25 is provided on its outer surface with a plurality of radiating ribs 127 which cause the air to be thrown outwardly by centrifugal action and thus stimulates 251 the circulation of such air through the motor. The air as it is thrown outwardly is forced into the passages 54 between the flanges 52 and 51 of the rear stator side plate 50 through which 301 passages it is passed. The air coming from the 301 passages 54 strikes the outer casing 83 passing between this casing and the outer periphery of the stator side plate and stator flange 66. The air is then deflected inwardly and outwardly by the alternate baffle plates 84 of the casing and 351 the fins 82 of the stator until it reaches the opposite or front side of the device where it then passes between the casing and the outer periphery of the front stator side plate 56 and flange 401 of the cylinder. The air now passes inwardly 401 through the plurality of spaces 60 formed between the flanges 57 and 58 of this stator plate and is deflected outwardly through the openings 46 in the front supporting frame by means of the annular baffle rings 61 and 47. It will thus 451 be seen that cooling air is conducted through the interior of the motor and then forced outwardly to the periphery of the cylinder where through its tortuous passage it picks up radiant heat caused by the burning gases and thus effectively 501 cools the motor.

Mounted within the outwardly extending hub 35 of the front supporting disc 26 is a drive flange 128. This flange is provided with an inwardly extending cylindrical ring 130 which is preferably 551 keyed or otherwise non-rotatably secured to the hub 35 of the disc 26. This flange provides means for taking power from the engine. It is preferably provided with a closed centrally arranged disc 131 which provides a cover for the bearing 601 27 at that end of the device.

At some point in the cylinder near the place where the expansion chamber 68 is first formed, I provide a boss 132 in which is screwed a spark plug 133 for igniting the charge.

Referring to Figs. 7 and 8, I show one means by which the spark plug may be timed and operated. As here shown, the wall 15 of the rear supporting frame 11 is formed with a recess 135. In this recess is mounted two contact points 136 701 which are carried by arms 137 each attached to an insulated block 138. The arms are secured in place by pins 139 which provide contact points for the wire used in the ignition system. The block is slidably mounted within a recess 140 751

whereby the contact points may be moved backwardly and forwardly so as to change the timing of ignition. The hub 126 of the rear rotor supporting disc 25 is provided with cam shaped projections 141 equal in number to the number of cylinders of the engine. Obviously, the pins 139 are connected with the spark plug 133 and with the source of current, as, for instance, a battery 178, through a suitable induction or spark coil 179.

In Fig. 6 I show a modification of my invention as well as a system of lubrication. In the construction shown in this figure the outer diameter of the complete device may be reduced somewhat since the guides 145 of the follower 146 extend beyond the center of the follower. In this form the centrally arranged shaft 147 does not extend through the follower as in the form of Fig. 1 but terminates at the rear of the follower. The follower in this form is provided with a central boss 148 which is suitably carried by a ball bearing 149 mounted within the end of the stationary shaft 147. In this form there is but one cam disc 150. The yoke 151 connecting the parts 152 and 153 of the piston rod carries at one side a roller 144 which engages with the cam groove of the cam disc and operates the pistons in a manner identical with the operation of the form of Figs. 1 and 2. The cam disc 150 is, of course, rigidly and non-rotatably attached to the shaft 147. The rear rotor supporting disc 154 is provided with a hub 155 which is rotatably supported by the roller bearing 156. The shaft 147 in this form as in the other form carries the rear supporting frame 157. The front rotor supporting disc 158 is identical with the front rotor supporting disc 26 of the other form of invention and it is provided with the roller bearing 32 located between it and the forward supporting frame 30. For clearness of illustration, the front supporting frame with its bearings and the stator and rotor parts of the construction are not shown in Fig. 6 since they are identical with the other form previously shown. The front rotor supporting disc is provided with vanes 159 and the rear rotor supporting disc 154 is provided with openings 160 for the circulation of cooling air in a manner similar to the other form above described.

In this form of my invention I show one method of lubricating the working parts of the device, but obviously other means may be employed with equal efficiency. In this form of invention the shaft 147 is provided with a large centrally arranged recess 161 which acts as an oil reservoir and within which is mounted an oil pump 162. The pump comprises a casing 175 and an impeller 176. The impeller of the pump is connected to a shaft extension 163 formed on the central boss 148 of the follower. The impeller of the pump is, therefore, driven by the rotation of the central boss. The shaft extension and the central boss is provided with a centrally arranged oil passageway 164 which communicates with the reservoir 161 through the opening 177 of the impeller which supplies the proper amount of lubricant to the bearings of the follower for the piston rod sleeves 153. The yoke 151 is provided with a central oil passageway 165 through which lubricant can pass to the piston rod sleeve 152 and thence to the piston and its working surfaces. The yoke is provided with a lateral passageway 166 whereby the bearing of the roll 144 is properly lubricated, as well as the groove of the cam disc 150. The level of the lubricant in the recess 161 is shown and the tube 167 which leads into the

recess 161 through opening 168 comes preferably from the drain in the sump of the oil separator 78, or it may get its source of supply from any other suitable means. The pump 162 feeds lubricant into a passageway 169 in the bottom wall of the shaft 147 and a lateral passageway 170 connects the passage 169 with the other lateral passage 171 to which a tube 172 is connected. This tube is led to any other working parts of the engine which need lubrication. It will be obvious that due to centrifugal force lubricant will be thrown outwardly to the rotor and stator working surfaces.

Since my invention is of the two-cycle type, the charge is drawn into each of the cylinder 15 sleeves, compressed and expanded, after which the burned gases are scavenged from the expansion chamber. In Fig. 1 of the drawings I show the piston of sleeve 90 on its intake stroke. Obviously, the intake stroke begins when the rollers 106 enter the lower eccentric portion of the cam groove 108 of the cam disc. The position of this portion of the groove with relation to the intake ports 70 is preferably such that the piston starts to its inward movement within the sleeve 25 before the ends of the intake ports 70 are reached so as to create a slight vacuum within the sleeve which will stimulate the flow of combustible mixture in the intake ports just as soon as the opening 96 of the sleeve is uncovered by the rotor in 30 its circular movement about the stator. From this point on until the center line of the piston is coincident with the vertical center line of the motor, the piston will be moved inwardly within the sleeve thus drawing into the sleeve a maximum charge of fuel mixture from the carburetor attached to the flange 73. It is preferable that the inlet passageways 70 terminate at such a point that the opening 96 of the sleeve is covered by the stator wall before the piston has 40 reached the vertical center line of the engine since a seal will thus be formed at the start of the compression stroke. From a point in the rotation of the rotor where the axis of the piston reaches the vertical center line of the motor to 45 substantially the point occupied by the piston carried by the sleeve 92, the piston will be moved outwardly within the sleeve thus compressing the charge. When it reaches the position occupied by the piston of the sleeve 92 the sleeve due 50 to the eccentric portion will be opened into the expansion chamber 68 formed between such sleeve and the leading bar 110 preceding the piston being discharged. During the inlet and compression strokes of the engine, the sleeves 91, 92 55 and 93 will be forced outwardly by centrifugal action and will have the outer face of the flange 95 of each thus held in firm contact with the concentric wall of the stator, whereby leakage around the space between the stator and rotor 60 will be prevented. This expansion space is, as shown in Fig. 1, relatively small when the gas is let into it but during the rotation of the rotor this expansion chamber will be ever increasing in volumetric capacity so as to provide for the expansion of the gases during the power cycle of the motor. During this power cycle the piston will be kept within the sleeve so as to close it against the entrance of the explosive gases since the portion of the groove 108 through which the 70 rollers 106 are now traveling is concentric with the central shaft 10. The expansion cycle will continue from the point where ignition occurs until the leading bar of the piston being described reaches the exhaust passage or port 74, 75

at which time the gases will be allowed to escape through such port and the separator 78. The leading bar 110 which precedes the next succeeding piston seals the expansion chamber of the piston just described and after the leading bar of the piston just described has opened into the exhaust port the next succeeding leading bar will scavenger all of the burned gases from the expansion chamber preceding it. Any desired number of pistons may be employed in my structure and for illustrative purposes I have shown three. Where three pistons are employed, it is obvious from Fig. 1 that as one expansion chamber is just about to be opened to the exhaust port 74 previously compressed gas of the next succeeding cylinder has been allowed to enter the next succeeding expansion chamber and is about to be ignited. Also at this period in the rotation of the rotor, the sleeve of the third piston is receiving a fresh charge of combustible mixture through suction produced by the inwardly traveling piston of that sleeve. There is, therefore, a constant torque produced upon the driving flange in my motor during its operation, as just above described. It is obvious that the follower 103, being rotatably mounted upon the shaft 10 will follow the rotation of the rotor and provide suitable bearing for the parts 101 of the reciprocating piston rods 100. During the intake and compression strokes as just above described, the sleeves 91, 92, and 93 are held within the cylinders 94 by contact with the concentric inner surface of the stator. When, however, the cylinders reach the points in their rotation where the power and expansion cycle of this operation occurs, the pressure of the expanding gases will, due to the area of the flanges 95 of the sleeves, keep the sleeves pressed inwardly and seated within the cylinders 94 and thereby counteract centrifugal force which would tend to move them out against the stator wall.

These and other modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described my invention, what I claim is:

1. A rotary engine comprising a stator, a rotor rotatably mounted within the stator, the stator and rotor being so formed that an expansion chamber is provided between portions of their peripheries, a plurality of radially arranged cylinders carried by the rotor, a piston sleeve slidably mounted within each of the cylinders for preventing gas leakages around the space between the stator and rotor during the inlet and compression strokes of the engine and formed with an apertured head flange, a reciprocating piston mounted within each sleeve, and cam means for causing the reciprocation of the pistons in timed relation to the cycle of operation of the motor.

2. A rotary engine comprising a rotor having a concentric outer periphery, a stator surrounding and enclosing the rotor and having its inner periphery formed with a concentric portion and an eccentric portion, the eccentric portion forming, with the rotor, an expansion chamber, the rotor being formed with a plurality of radially arranged cylinders, a piston sleeve slidably mounted within each of these cylinders and formed with

an apertured head flange for engagement with the concentric portion of the stator whereby gas leakages around the space between the stator and rotor during the inlet and compression strokes of the engine are prevented, the area of the sleeve head flange being such that when exposed to the expanding gases it will be kept seated within the cylinder, a reciprocating piston mounted in each sleeve, and cam means for reciprocating the pistons in timed relation with the cycle of operation of the motor.

3. A rotary engine comprising a rotor having a concentric outer periphery, a stator surrounding and enclosing the rotor and having its inner periphery formed with a concentric portion and an eccentric portion, the eccentric portion forming, with the rotor, an expansion chamber, the rotor being formed with a plurality of radially arranged cylinders, a piston sleeve slidably mounted within each of the cylinders and formed with an apertured head flange for engagement with the concentric portion of the stator whereby gas leakages around the space between the stator and rotor during the inlet and compression strokes of the engine are prevented, the area of the sleeve head flange being such that when exposed to the expanding gases it will be kept seated within the cylinder, a reciprocating piston mounted in each sleeve, a follower rotatable with the rotor, a piston rod carried by each piston and guided by the follower, a roller carried by each piston rod, and cam means engaging the rollers for reciprocating the pistons in timed relation with the cycle of operation of the motor.

4. A rotary engine comprising a centrally arranged stationary shaft, a front rotor supporting disc and a rear rotor supporting disc rotatably mounted at opposite ends of the shaft, a rotor carried by said discs, front and rear stator side plates in bearing contact with the side surfaces of the rotor, a stator non-rotatably carried by the side plates, a rear supporting frame carried by the shaft and secured to the rear stator side plate, and a front supporting frame secured to the front stator side plate, thus providing a rigid support for the front rotor supporting disc.

5. A rotary engine comprising a centrally arranged stationary shaft, a front rotor supporting disc and a rear rotor supporting disc rotatably mounted at opposite ends of the shaft, a rotor carried by said discs, front and rear stator side plates in bearing contact with the side surfaces of the rotor, a stator non-rotatably carried by the side plates, a rear supporting frame carried by the shaft and secured to the rear stator side plate, a front supporting frame secured to the front stator side plate, thus providing a rigid support for the front rotor supporting disc, and a jacket surrounding the stator in interspaced relation therewith, the front supporting frame, the front and rear rotor supporting discs, and the front and rear stator side plates being provided with passageways whereby air is circulated through the motor.

6. A rotary engine comprising a centrally arranged stationary shaft, a front rotor supporting disc and a rear rotor supporting disc rotatably mounted at opposite ends of the shaft, a rotor carried by said discs, front and rear stator side plates in bearing contact with the side surfaces of the rotor, a stator non-rotatably carried by the side plates, a rear supporting frame carried by the shaft and secured to the rear stator side plate, a front supporting frame secured to the front stator side plate and giving

rigid support to the front rotor supporting disc, a jacket surrounding the rotor in interspaced relation therewith, the front supporting frame, front and rear supporting discs, and front and rear stator side plates being provided with passageways for passing cooling air through the motor, the rotor being provided with a centrally arranged septum, openings formed in the septum near the rotor, and means engageable with the inner edge of the septum for preventing air passing across from one rotor supporting disc to the other without passing through the septum openings.

7. A rotary engine comprising a centrally arranged stationary shaft, a front rotor supporting disc and a rear rotor supporting disc rotatably mounted at opposite ends of the shaft, a rotor carried by said discs, front and rear stator side plates in bearing contact with the side surfaces of the rotor, a stator non-rotatably carried by the side plates, a rear supporting frame carried by the shaft and secured to the rear stator side plate, a front supporting frame secured to the front stator side plate thus providing a rigid support for the front rotor supporting disc, a plurality of reciprocating pistons carried by the rotor, cam means rigidly carried by the shaft, and means co-acting with the cam means for causing the reciprocation of the pistons in timed relation with the cycle of operation of the motor.

8. A rotary engine comprising a centrally arranged stationary shaft, a front rotor supporting disc and a rear rotor supporting disc rotatably mounted at opposite ends of the shaft, a rotor carried by said discs, front and rear stator side plates in bearing contact with the side surfaces of the rotor, a stator non-rotatably carried by the side plates, a rear supporting frame carried by the shaft and secured to the rear stator side plate, a front supporting frame secured to the front stator side plate and giving rigid support to the front rotor supporting disc, a plurality of reciprocating pistons carried by the rotor, cam means rigidly carried by the shaft and means co-acting with the cam means for causing the reciprocation of the pistons in timed relation with the cycle of operation of the motor, the cam means

having an outer periphery concentric with the shaft, the rotor being formed with an inwardly extending septum formed with openings near the rotor, and baffle means carried by the septum and engaging the concentric periphery of the cam means, whereby air passing through the rotor will be deflected through the openings of the septum.

9. A rotary engine comprising a centrally arranged stationary shaft, a front rotor supporting disc and a rear rotor supporting disc rotatably mounted at opposite ends of the shaft, a rotor carried by said discs, front and rear stator side plates in bearing contact with the side surfaces of the rotor, a stator non-rotatably carried by the side plates and provided with radiating fins on its outer surface, a rear supporting frame carried by the shaft and secured to the rear stator side plate, and a front supporting frame secured to the front stator side plate, thus providing a rigid support for the front rotor supporting disc, and a jacket surrounding the rotor in interspaced relation therewith and provided with baffle plates in staggered relation with the radiating fins of the stator, the front supporting frame, front and rear supporting discs, and front and rear stator side plates being provided with passageways whereby air is circulated through the motor.

10. A rotary engine comprising a centrally arranged stationary shaft, a front rotor supporting disc and a rear rotor supporting disc rotatably mounted at opposite ends of the shaft, a rotor carried by said discs, front and rear stator side plates in bearing contact with the side surfaces of the rotor, a stator non-rotatably carried by the side plates, a rear supporting frame carried by the shaft and secured to the rear stator side plate, a front supporting frame secured to the front stator side plate, thus providing a rigid support for the front rotor supporting disc, a plurality of radially arranged cylinders carried by the rotor, a piston sleeve mounted within each cylinder, and a reciprocating piston mounted within each sleeve for supplying a charge of compressed combustible mixture directly to the expansion chamber.
